UNITED STATES PATENT OFFICE.

MILTON C. JONES, OF GREEN ISLAND, NEW YORK.

STEAM-BOILER FURNACE.

SPECIFICATION forming part of Letters Patent No. 252,040, dated January 10, 1882.

Application filed September 16, 1881. (No model.)

To all whom it may concern:

Be it known that I, MILTON C. JONES, of Green Island, in the county of Albany and State of New York, have invented certain new and 5 useful Improvements in Steam - Boiler Furnaces, of which the following is a specification.

My invention relates to improvements on the invention for which Letters Patent No. 220,827 of the United States were granted to me on the 10 13th day of July, 1880; and the objects of my present improvements are, first, to afford greater protection to the air-box or top jamb-plate against the destructive effect of the intense heat generated in the furnace; second, to provide 15 suitable protection for the front plate of the furnace at the sides of the furnace-door opening; and, third, to utilize the currents of air that pass through the protecting-chambers, wherein they are heated and from whence they 20 are conveyed beneath the fire - grates to promote the combustion of the fuel in the furnace.

In the accompanying drawings, which form part of this specification, and to which reference is made herein, Figure 1 is a detached perspective view of the under side of my improved air-box or top jamb-plate; Fig. 2, a front elevation, and Fig. 3 an end elevation, of the same; Fig. 4, a front elevation of a boiler-furnace containing my improvements, showing portions of 25 the front plate, brick-work, &c., broken away for the purpose of exposing the underlying parts; Fig. 5, a partial plan view and horizontal section of Fig. 4, and Fig. 6 a longitudinal section of Fig. 4.

As represented in the drawings, A indicates the air-box or top jamb-plate; B, the side jamb-plates; D, dead-plate of furnace; E, iron front plate; F and G, hot-air flues; H, hot-air-escape pipes; I, ash-pit; J, fire-grates, and K 30 steam-pipes.

The top jamb-plate, A, is fixed over the top of the furnace-door to protect the front plate of the furnace at that point. To better preserve said jamb-plate from the destructive effect of the intense heat of the furnace I preferably make its cross-section of a triangular form, and provide its lower or inclined side with dovetailed snugs a , for receiving protecting-plates A' , of fire - brick or other suitable 45 heat-repelling material. Said protecting-plates are provided with dovetail portions a' , that fit

into the space between the snugs a , and with wings a^2 , that extend over said snugs to protect them from the heat.

For the purpose of facilitating the removal 55 and renewal of the protecting-plates A' while the jamb-plate is retained in its position in the furnace, a portion of the lower snug a equal to the width of one of the plates A' is omitted and its place supplied by a detachable 60 fastening-piece, a^3 . By this arrangement the plates A' can be inserted in the vacant space and slid into their places between the snugs a , and when the last one of the plates A' is inserted the fastening-piece a^3 is secured in place 65 by means of bolts.

The jamb-plate A is divided by vertical partitions a^4 into the longitudinal flues a^5 and a^6 , which connect, at a^7 , near or at the middle of the jamb-plate. When the top jamb-plate, A, 70 is used alone the external air is admitted into its flue a^5 through the opening a^8 , and after passing through said flue, opening a^7 , and flue a^6 , and thereby becoming highly heated, it (the air) may escape through the hot - air - escape 75 pipes a^9 , or, when preferred, from pipes leading from the ends of the flue a^6 ; but in either case the heated air may be conveyed through suitable ducts and discharged at any desired point.

As shown in Fig. 5, the side jamb-plates, B, are fixed at both sides of the furnace - door. They run at an angle from the sides of the door to the sides of the furnace, and extend upward from the dead-plate D to the under side of the 85 top jamb-plate. The back side of the side jamb-plate, B, is provided with a division-plate, b, by which, together with the brick - work and iron front plate of the furnace, the reversible flue b' is formed behind each of said side jamb- 90 plates. The said side jamb-plates have their exposed faces covered by protecting-plates B' , of fire-brick or other suitable heat-repelling material, and for the purpose of retaining said protecting-plates in place a dovetail snug, b^2 , 95 is formed near the front edge of the jamb-plate to receive a counterpart dovetail on the protecting-plate, and the rear side of the latter is secured by means of a screw - bolt, b^3 , which, from preference, is inserted in a countersunk 100 hole in the face of the protecting-plate.

Air from the surrounding atmosphere is ad-

mitted into the revertible flues *b* through openings *e* in the iron front plate, *E*, of the boiler-setting. The air, after entering the openings *e*, passes, as indicated by the arrows in Figs. 4 and 5, through the revertible flues *b'*, thence through the vertical flues *F*, formed in the brick-work of the boiler-setting, into the flue *a⁵* of the top jamb-plate, *A*, and after passing through the flue *a⁵* and opening *a⁷* it is reverted outward through the flues *a⁶* into the flues *G*, which extend through the side walls of the boiler-setting and connect with the escape air-pipes *H*, by which the air (which has now become intensely heated) is discharged into the ash-pit *I*, beneath the furnace-grates *J*. For the purpose of accelerating the flow of air through the flues in the jamb-plates *A* and *B*, a current of steam from the boiler is conveyed through the pipes *K*, which enter the lower horizontal portions of the pipes *H*, so that the steam will be discharged in line with the axial centers of said horizontal portions of the last-named pipes, and in this manner currents of mingled hot air and steam are injected under pressure beneath the grates *J*, and are there utilized in promoting the combustion of the fuel in the furnace.

When preferred the hot-air-escape pipes *H* may be arranged to deliver the heated air at any point other than the ash-pit, and in such cases the steam-currents may be dispensed with.

I claim as my invention—

1. The top jamb-plate, *A*, provided with partitions *a⁴* for forming the flues *a⁵* and *a⁶*, and connecting - passage *a⁷*, as herein described, in combination with protecting - plates *A'*, of fire-brick or other suitable heat-repelling material, detachably connected to said jamb-plate, as herein specified. 35

2. The combination, with the side jamb-plates, *B*, revertible flues *b'*, and inlet air-openings *e*, of the top jamb-plate, *A*, provided with flues *a⁵* and *a⁶*, connected to the flues *b'* by means of the flues *F*, and to the hot-air-escape 45 pipes *H*, as and for the purpose herein specified.

3. In a steam-boiler furnace, the combination, with top and side jamb-plates for the furnace-door, made separately and connected, as herein described, to form continuous air-circulating flues extending from the air-inlet openings to the hot-air-escape pipes, of the hot-air-escape pipes *H*, provided with steam-pipes *K*, arranged in relation to said escape-pipes as herein described, for the purpose of forcibly injecting currents of mingled hot air and steam into the furnace, as herein specified. 50

MILTON C. JONES.
